UNITED STATES PATENT OFFICE

MORTON HAVENS, JR., OF ALBANY, NEW YORK.

DESIGN FOR A BRANCH BOX FOR INSULATED ELECTRIC WIRES.

No. 39,765.

Specification for Design.

Patented Jan. 12, 1909.

Application filed February 16, 1906. Serial No. 301,510. Term of patent 7 years.

To all whom it may concern:

Be it known that I, MORTON HAVENS, Jr., a citizen of the United States, residing and having my post-office address at No. 79 Chapel street, in the city of Albany, county of Albany, and State of New York, have invented a new, original, and ornamental Design for a Branch Box for Insulated Electric Wires.

In the accompanying drawings, Figure 1 is a perspective view of a branch box for insulated electric wires, embodying my design, and Fig. 2 is a perspective view of said branch box shown as inverted.

This design for branch boxes comprises an elongated body having a cap or closure upon

one side, constituting a continuation of the lines of the body, and the opposite side of the elongated body is provided with curved sides and one curved end. A nipple projects from one end and the closure is provided with an upright central projection, all of the parts being joined by gradual curves.

What I claim is:

The ornamental design for a branch box for insulated electric wires, substantially as herein shown and described.

MORTON HAVENS, JR.
